his Atty.

UNITED STATES PATENT OFFICE.

EDWARD B. NIMMO, OF BROOKLYN, NEW YORK, ASSIGNOR, BY MESNE
ASSIGNMENT, TO WALTER WINTHROP, OF SAME PLACE.

STYLOGRAPHIC FOUNTAIN-PEN.

SPECIFICATION forming part of Letters Patent No. 226,925, dated April 27, 1880.

Application filed June 24, 1879.

To all whom it may concern:

Be it known that I, EDWARD B. NIMMO, of Brooklyn, Kings county, New York, have invented certain new and useful Improvements 5 in Stylographic Fountain-Pens, of which the following is a specification.

My invention relates to that class of pens sometimes called "stylographic," having a reservoir-handle tapering at one end and terminating in a capillary tube, with an internally-vibrating needle or stylus, which forms the writing-point.

My present invention is in part an improvement on a former application, filed April 26, 1879, and also embodies original devices; and it relates to the construction of the vibrating needle and its manner of mounting; also, to the construction of the air-vent of the reservoir and to the vent-cap thereof, all of which 20 embody novel features, as hereinafter fully set forth.

In the drawings, Figure 1 is an enlarged longitudinal section of my improved pen, and Fig. 2 represents the needle or stylus and its sustaining-arm removed from the tip and viewed flatwise or at right angles to its position in Fig. 1.

As illustrated, *a* indicates the usual hollow or tube handle of the pen, forming the ink-reservoir, and *b* its removable tip, which, in the usual manner, screws into the lower end of the handle, incloses the vibrating needle, and terminates with the capillary tube *c*, through which the needle vibrates.

The vibrating needle-tongue or stylus is indicated at *d*, and is of that kind shown in my former application—viz., it is laterally and longitudinally flexible, forming in itself a spring, so that under the variable pressure of writing 40 it yields longitudinally and bows laterally, and thus, by its own elasticity, performs the necessary vibrating action.

The needle is secured at the inner end, as also shown in said application, to a threaded ring, *e*, which screws into the conical tip, as seen in Fig. 1. A novel feature, however, is the rigid sustaining-arm *f*, which is fixed to and projects from the ring *e*, and extends in line with the tongue to beyond the middle 50 thereof, where it is crooked and bent at right

angles, terminating in an eye, *g*, through which the tongue is guided, as shown. The tongue is inserted in this eye through a narrow slit, *h*, through which it is passed edgewise, and, being turned flatwise when it enters the eye, 55 it is thus secured against displacement, as shown in Fig. 2.

The inner end of the tongue is secured in place by the removable fastening-wedge *i*, which is driven in between the inner surface 60 of the ring *e* and the outer face of the arm *f*, which latter is secured to the ring in the position of the chord of a circle, as will be fully understood from Fig. 2, thus forming a secure and simple means of fastening the tongue, and 65 one which admits of adjusting the position of the tongue in or out, so that its point may project the required distance from the capillary tube. Now, from the fixed end of the tongue to the point where it passes through the eye of 70 the arm *f* it is flat and thin, and is quite flexible or springy, while the portion beyond the arm is round and practically rigid, so that the elastic and delicate portion of the tongue is guarded by the rigid arm. At the point where 75 the tongue projects beyond the arm, or where the rigid and flexible portions blend, however, a lateral offset or shoulder, *k*, is formed on the tongue, which is normally separated a slight distance from the end of the arm, but which, 80 when the tongue is pressed inward, strikes against the end of the arm, and thus forms a stop, which limits the vibration of the tongue and prevents its being forced quite beyond the tip of the capillary tube, and also prevents too 85 much pressure bearing on the flexible portion of the tongue, as will be readily understood. The sustaining-arm thus supports and protects the delicate tongue throughout the main portion of its length, and also forms a means 90 of stopping or limiting its movement, and enables the tongue to be inserted in or removed from the conical tip without danger of injury, to which it is liable when not thus supported.

The end of the arm *f*, which projects from the upper edge of the ring *e*, forms a handle, *l*, by which the ring and its attachments may be screwed in or out of the tip, and this handle has a projecting cross-bar or shoulder, *m*, 95

which strikes against the edge of the tip and prevents the ring, &c., being screwed in too far, and thus determines its proper position.

It will be readily understood that any equivalent form of stop between the end of the arm *f* and the tongue may be used in place of that shown. Thus a small pin may project laterally from the tongue into a short longitudinal slot on the arm; but I prefer the eye on the end of the arm, with the lateral notch or shoulder on the tongue, as illustrated.

Another feature of my invention lies in an improved form of air-vent to admit the gradual outflow of the ink.

15 *m* is the vent-plug, which fits tightly into the top of the reservoir, as usual, and its outer end, which is threaded, receives the vent-cap *n*, by screwing which up or down, so as to cover or uncover a small hole, *o*, communicating with the interior, the admission of air is regulated as required.

Heretofore the vent-plug has been formed with a long air-tube extending therefrom to the bottom of the ink-reservoir; but this tube 25 I dispense with, and I form the plug with a short tubular neck, over which is fastened a small cap or tube, *p*, of soft vulcanized rubber or equivalent elastic material, as shown in Fig. 1. This tube or cap projects but a short 30 distance into the reservoir, and its lower end is closed, while one or more fine cuts or slits, *r*, are made preferably on its sides by a sharp blade, thus forming, as will be readily understood, a delicate self-acting air-valve, which admits a 35 slow infiltration of air to the reservoir to allow the gradual outflow of the ink from the tip of the pen.

It will be readily seen that this form of air-vent is simpler and less expensive than the 40 long air-tube, and, moreover, does not occupy and partly obstruct the reservoir, as does the latter; and, furthermore, it admits the air very gradually, as is required, and continues its function on the very last drop of ink in the 45 reservoir, whereas the long air-tube permits the ink to run out too fast after the level has fallen below its extremity.

The remaining features of my invention lie in the formation of the upper extremity of the 50 handle or the vent-cap and plug thereof.

Thus it will be seen that the vent-cap *n* is a short continuous tube or elongated ring, one open end being screwed into the threaded part of the vent-plug *m*, while the opposite open 55 end is adapted to form a socket to receive the tip-cap *s* when removed from the tip. The vent-plug *m*, which forms the upper extremity of the pen-handle, preferably terminates in a slender shank, *t*, which rises centrally in the 60 bore of the vent-cap *n*, but terminates flush with its upper end, as shown, and the tip-cap

s preferably fits tightly over this shank and loosely in the bore of the vent-cap *n* when socketed thereon. The central stem, *t*, may, however, be omitted, and the tip-cap socketed 65 tightly in the bore of the vent-cap, as will be readily understood.

This construction of the described parts, as will be readily observed, obviates the objection of having a salient projection on the top 70 of the handle, as usual in these pens, and which is liable to catch in the pocket.

I lay no claim in this application to the tubular plug or holding-ring carrying the vibrating needle, and fixed to or adjustable in the 75 case of the instrument, or in the lower section or tip thereof, having shown this feature in my former application, above referred to.

What I claim is—

1. The combination, in a stylographic fountain-pen, of the elastic tongue *d* and the rigid arm *f*, extending in line with the tongue to about the middle thereof, and arranged to support and guide the same, substantially as herein shown and described. 80

2. The elastic tongue *d*, formed with a lateral stop-shoulder, *k*, in combination with the rigid arm *f*, formed with an eye, *g*, to guide the said tongue and stop the said shoulder, substantially as herein shown and described. 85 90

3. The combination, with the ring *e*, elastic tongue *d*, and arm *f*, of the fastening-wedge *j*, arranged and operating substantially as shown and described.

4. The combination, with the ring *e* and an 95 elastic tongue secured thereto, of the handle *i*, formed with the stop-shoulder *l*, substantially as and for the purpose set forth.

5. In a stylographic fountain-pen, a flexible 100 vibrating tongue, *d*, having its outer portion rigid and its inner portion flexible or elastic, and mounted on a rigid sustaining-arm, *f*, arranged to extend toward the rigid portion of the tongue, with its end adapted to guide the tongue, substantially as herein shown and described. 105

6. In a stylographic fountain-pen, an air-vent, consisting of a hollow or tubular plug, *m*, and an elastic or rubber cap, *p*, having one or more fine slits, *r*, adapted to allow the slow 110 infiltration of air, substantially as herein shown and described.

7. A stylographic fountain-pen having the upper extremity of its handle constructed with an annular recess having a central stem rising 115 therein flush, or nearly so, with the top of the recess to receive the tip-cap *s*, substantially as herein shown and described.
